DESIGN FOR A CARPET.

SPECIFICATION forming part of Design No. 12,785, dated February 21, 1882.

Application filed December 17, 1881. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design is composed of a large free-hand bouquet, A, composed of flowers, sprays of foliage, and elongated leaves or blades of grass, and the smaller bouquets B C, the elements of said bouquets being arranged so that sprays

and leaves project therefrom in all directions over the ground of the carpet, as shown. 15

I claim—

The design for a carpet, substantially as shown and described.

In testimony whereof I have signed my name to this specification, in the presence of two subscribing witnesses, this 12th day of December, A. D. 1881.

THOMAS J. STEARNS.
